PAIR OF SPECTACLES

Norman J. Radziwon, Rochester, N.Y., assignor to
Bausch & Lomb Incorporated, Rochester, N.Y., a corporation of New York

Filed Sept. 27, 1962, Ser. No. 71,882

Term of patent 14 years

(Cl. D57—1)

FIG. 1

FIG. 2

FIG. 4

FIG. 3

FIG. 1 is a front view of a pair of spectacles showing my new design;

FIG. 2 is a side view of said pair of spectacles taken from the right side thereof as viewed in FIG. 1;

FIG. 3 is a top view of said pair of spectacles; and

FIG. 4 is a cross-sectional view of the bridge portion of the pair of spectacles taken on the line 4—4 of FIG. 1.

The side not shown has substantially the same appearance as the side shown. The temple is shown broken away in FIG. 3 for convenience of illustration. The drawing is stippled to show contrast.

I claim:

The ornamental design for a pair of spectacles, substantially as shown and described.
